UNITED STATES PATENT OFFICE.

HERBERT E. DAVIDSON, OF BOSTON, MASSACHUSETTS.

DRAWER FOR HOLDING INDEX-CARDS.

SPECIFICATION forming part of Letters Patent No. 470,884, dated March 15, 1892.

Application filed September 23, 1890. Serial No. 365,926. (No model.)

To all whom it may concern:

Be it known that I, HERBERT E. DAVIDSON, of Boston, in the county of Suffolk and State of Massachusetts, have invented a new and 5 useful Improvement in Drawers for Holding Index-Cards, of which the following, taken in connection with the accompanying drawings, is a specification.

This invention has for its object to improve 10 drawers or boxes to contain cards for use in libraries and other places where cards are used for the purpose of indexing.

In accordance with my invention the box or drawer to receive the cards is provided 15 with a rod, which is extended through one end of the drawer and through holes in the cards, the said rod being provided with threads or projections to engage the threaded interior of a bushing let into the end of the 20 drawer, the said bushing being threaded, preferably, externally to be screwed into the end of the drawer, the bushing being securely held in place in the end piece.

Figure 1 shows part of a box or drawer embodying my invention, the rear end and one-half the box or drawer being broken away, the figure showing some cards in place and part of the follower-block. Fig. 2 shows part 25 of the front end of the drawer and the threaded bushing, and Fig. 3 shows the key to lock the bushing.

The box or drawer D, composed of wood, has in practice four sides or ends and a bottom piece, the drawings, Fig. 1, representing 30 the drawer as in longitudinal section, the rear end of the drawer being also broken off. The follower E is a loose block resting in the drawer and adapted to back up the cards F. The front end of the drawer has inserted or 35 screwed into it a bushing C, preferably of metal and threaded both externally and internally, and, as shown, one end of the bushing has a screw-driver notch c, into which to enter a screw-driver by which to turn the bushing into place in the drawer. The card-holding rod B' has a threaded portion B and next it a head A, the threaded portion entering the bushing and engaging its internal threads when the rod B' has been inserted 40 to pass through holes in the cards and enter and preferably pass through the follower. The engagement of the threaded part of the holding-rod with the bushing prevents any accidental withdrawal or removal of the rod

B' from the cards or the box. The bushing 55 has a longitudinal groove or key-seat d, into which may enter a key g. (Shown in Fig. 3 as a piece of wire.)

As a finish to the front of the box or drawer and to prevent the shouldered under side of 60 the head of the rod from wearing on the wood-work, I have provided a plate b, which is held in place by a suitable screw b', one-half the said plate being shown in Fig. 1.

Having described my invention, what I 65 claim as new, and desire to secure by Letters Patent, is—

1. A box or drawer for the reception of cards and an internally-threaded bushing, combined with a card-holding rod having a 70 threaded portion at or near one end to engage the interior of the bushing and confine the rod in place, the remainder of said rod being smooth to pass through the cards, substantially as described. 75

2. A box or drawer and the bushing threaded externally and internally, externally to be turned into the end of the box or drawer and having a tool-receiving notch in one end, whereby it may be turned, combined with a 80 card-holding rod provided with a threaded part to engage the internal threads of the bushing, substantially as described.

3. A box or drawer and the bushing threaded externally and internally, externally to be 85 turned into the end of the box or drawer, combined with a card-holding rod provided with a threaded part to engage the internal threads of the bushing and with a wear or finish plate interposed between the head of 90 the rod and the front end of the box or drawer, substantially as described.

4. A box or drawer and the bushing threaded externally and internally, externally to be turned into the end of the box or drawer, 95 combined with a card-holding rod provided with a threaded part to engage the internal threads of the bushing and with a bushing-locking device, as g, to operate substantially as described. 100

In testimony whereof I have signed my name to this specification, in the presence of two subscribing witnesses, on this 2d day of August, A. D. 1890.

HERBERT E. DAVIDSON.
